DESIGN FOR A BUILDING BLOCK

Frank Bebar, Naperville, Ill.

Application July 19, 1939, Serial No. 86,084

Term of patent 14 years

To all whom it may concern:

Be it known that I, Frank Bebar, a citizen of the United States of America, residing at Naperville, in the county of Du Page and State of Illinois, have invented a new, original, and ornamental Design for a Building Block, of which the following is a specification, reference being had to the accompanying drawing forming a part thereof.

Figure 1 is a perspective view illustrating the building block showing my new design.

Figure 2 is a perspective view illustrating the opposite side of the building block.

I claim:

The ornamental design for a building block, as shown.

FRANK BEBAR.
